UNITED STATES PATENT OFFICE

JAMES WATSON, OF MARINETTE, WISCONSIN

WINDOW SCREEN

Application filed May 23, 1927. Serial No. 193,550.

This invention aims to provide novel means for connecting a screen to a slideable window sash, so that the screen may move with the sash, when it is desired to have the screen in position, the construction being such that the sash may be operated without the screen, when desired, the screen then being housed in an out of the way position within the window frame.

10 Other objects will be made manifest as the description proceeds, and it is to be understood that a mechanic, working within the scope of what is claimed, may make such changes as his skill may suggest, without departing from the spirit of the invention.

15 In the drawings:—

Figure 1 shows in elevation, a device constructed in accordance with the invention, parts being broken away, and parts being in section;

Figure 2 is a longitudinal section of the structure shown in Figure 1;

Figure 3 is a cross section on the line 3—3 of Figure 1;

20 Figure 4 is a sectional view showing the latch and the keeper mechanism;

Figure 5 is a longitudinal section of the latch and keeper mechanism, where in parts appear that have been sectioned away in Figure 4;

Figure 6 is a transverse section taken through the sash and the latch mechanism;

Figure 7 is a fragmental section taken about on the line 7—7 of Figure 1;

25 Figure 8 is an elevation showing a slight modification in the latch mechanism;

Figure 9 is a transverse section of the structure depicted in Figure 8.

Figure 10 is a perspective view showing one corner of the screen.

The invention is shown in the drawings, as applied to a window which consists of a single vertical sliding sash, but it is to be understood that the invention may be embodied, as well, in a two-sash window, the change being merely one of duplication, and calling for no specific illustration.

30 The window frame is marked by the numeral 1 and includes stiles 2 connected by a sill 3 carrying a table 11. Guide strips 4 and 5

extend upwardly from the sill 3 and are mounted on the stiles 2. Guide grooves 6 are formed in the stiles 2, between the guide strips 4 and 5, the grooves 6 extending both upwardly and downwardly with respect to 55 the sill 3. At a point well above the sill 3, the guide grooves 6 have transverse extensions 7, the utility of which will be made manifest hereinafter. A slot 8 is formed in the sill, in the same plane with the guide grooves 6. A 60 plate 9, preferably made of metal, is secured to the sill 3, and has an upstanding rib 10.

A screen, marked generally by the numeral 12, is mounted to slide in the guide grooves 6. When the screen 12 is not in use, it is lowered, 65 as indicated in Figures 1 and 2, and lies below the sill 3. The screen slides through the slot 8 in the sill 3. The screen 12 is made up of a bottom rail 14, side rails 15, and a top rail 16, the rails being made of metal, and being

connected together, and to the foraminous body 19 of the screen, in any desired manner, the edges of the body 19 of the screen being received within the rails 14, 15 and 16. The bottom rail 14 and the side rails 15 are

70 U-shaped in transverse section, whereas the top rail 16 has side walls which are extended laterally to form a transverse flange 17, the flange 17 being connected to an upstanding bead 18 which is U-shaped in transverse section. In the bead 18 is mounted a metal rod 20 which, for the sake of reinforcement, preferably is as long as the bead. Intermediate its ends, the rod 20 is supplied with a U-shaped keeper 21 which extends upwardly through 75 the bead 18. As shown at 22 in Figure 1, the flange 17 and the bead 18 are cut away at their ends, so that the flange 17 does not extend out quite to the outer edges of the side rails 15.

As a result, the side rails 15 are 80 mounted to slide in the guide grooves 6, but the ends of the flange 17 merely slide on the exposed surface of the stiles 2, and the guide grooves 6 are narrow enough so that the ends of the flange 17 cannot enter the grooves.

When, however, the screen 12 is raised far enough, the screen can be moved horizontally, as shown by the arrow A in Figure 1, the ends of the flange 17 entering extensions 7 (Figure 2) at one side or the other of the window 85 90 95 100

frame. When the ends of the flange 17 enter one or the other of the extensions 7, the screen 12 may be moved horizontally in the direction of the arrows A, one of the vertical edges 5 of the screen frame being disengaged from the corresponding groove 6, whereupon the screen may be removed bodily from the window frame.

A sash 23 is slidable on the stiles 2 of the frame 1 between the guide strips 4 and 5. The sash 23 includes a bottom rail 24 provided in its lower surface with a groove 25 which is adapted to receive the rib 10 on the plate 9 to afford a tight closure when the sash 23 is lowered upon the sill 3 as shown in Figure 2. In the lower edge of the bottom rail 24 of the sash 23 there is a groove 26 which is adapted to receive the bead 18 on the screen 12, when the upper edge of the screen 15 is coupled to the lower edge of the sash 23, by a means which will be described hereinafter. In the vertical edges of the sash 23 there are grooves 27 which are aligned with the grooves 6 of the stiles 2, as shown in Figure 7. Weather strips 28, preferably made of metal, are mounted in the grooves 27 of the sash 23 and slide in the grooves 6 of the stiles 2. The weather strips 28 preferably are U-shaped in cross section, and have a little resiliency, so that they will tend to expand and have a good sliding fit in the grooves 6, without exerting too much drag when the sash 23 is raised and lowered. The strips 28 are held in place by any desired number of securing 30 elements 29, such as pins, mounted in the sash 23 and passing through the weather strips 28. The guide strips 5 overlap the pins 29 at their outer ends, and, consequently, the securing elements 29 cannot become detached accidentally, with a resulting loosening of the weather strips 28: but when the strips 5 are removed, then the pins 29 may be detached, and the weather strips 28 pulled out. This is done, generally, by raising the sash 23 45 and reaching up into the lower ends of the strips 28 with a suitable tool (not shown) the tool being received in the holes formerly occupied by one of the pins 29, and the weather strips then being pulled down and out of engagement with the sash 23.

A seat 30, which may be an auger hole, is formed in the lower edge of the bottom rail 24 of the sash 23, and in the seat 30 is located a latch casing 31 which is T-shaped in cross 55 section, the casing being provided with a foot plate 32, which is countersunk into and secured to the bottom rail 24 of the sash 23. Considered as to cross section, the latch casing 31 comprises a body 33 and a trough-shaped latch housing 34 disposed at right angles to the body and communicating with the body. Near to its upper end, the latch casing 31, has openings 35 and 36 which are disposed opposite to each other, as indicated 60 in Figure 5. A latch 37 is located for the

most part in the housing 34 and is mounted to swing on a pivot element 38 carried by the part 34. At its lower end, the latch 37 is beveled as shown at 39, the latch being supplied with a shoulder 40 disposed above the beveled portion 39. A spring tongue 41 is secured at one end to the latch 37, the lower end of the spring tongue 41 bearing slidably against the outer portion of the latch housing 34. The function of the spring 41 is to swing the lower end of the latch 37 inwardly, into the position shown in Figure 5, so that when the keeper 21 on the screen 12 enters the lower end of the body 33 of the latch casing 31, the keeper will first engage the inclined edge 39 of the latch 37 and tilt the latch, and then engage with the shoulder 40, as shown in Figure 5, the construction being such that when the sash 23 is raised and lowered, the screen 12 will be raised and lowered also. The latch 37 is supplied at its upper end with fingers 42 and 43, the finger 43 being accessible through the opening 35 in the latch casing 31, and the finger 42 being accessible through the opening 36. The fingers 42 and 43 are threaded, so that an operating member or knob 44 may be mounted on either of them, the knob extending outwardly through a wear plate 45 mounted on the bottom rail 24 of the sash 23 above the lifting piece 46. When the knob 44 is mounted on the finger 42, as in Figure 5, the latch 37 is operated by pushing on the button 44, to disengage the shoulder 40 from the keeper 21, whereupon the sash 23 may be raised and lowered independently of the screen 12, the screen remaining in concealed position below the sill 3, as shown in Figure 1.

Sometimes it may be desirable to operate the latch 37 by pull rather than by push, and, then, the knob 44 is detached from the finger 42 and is threaded on the finger 43, the knob moving in the opening 35.

The operation of the device has been dealt with hereinbefore, step by step, in connection with the structure, but, generally stated, the screen 12 may be raised and lowered along with the sash 23, because these parts are connected through the instrumentality of the latch mechanism shown in detail in Fig. 5; but if the operator wishes to raise and lower the sash 23, leaving the screen 12 in the concealed position of Figure 1, he may do this by tilting the latch 37 so as to free it from the keeper 21 on the screen 12.

Some persons may prefer a superficial latch casing to the one that is mounted in the bore or seat 30, as shown in Figure 5. Under such circumstances, recourse is had to the structures shown in Figures 8 and 9. In this form of the invention, parts hereinbefore described have been designated by numerals previously used, with the suffix "a". The latch housing 34^a and the body 33^a of the casing 31^a are made separate, and have flanges 46 130

mounted in a shallow recess 47 in the sash 23^a and held therein by securing elements 48, such as screws.

What is claimed is:—

5 In a device of the class described, a window frame provided at each side with stiles having guide grooves, each groove having a transverse extension, a screen slideable vertically in the grooves and including a transverse flange which is long enough so that both of its ends can engage with the exposed surfaces of the stiles at both sides of the window frame to prevent the screen from moving horizontally in the grooves and disengaging the vertical edges of the closure from the grooves, each end of the flange being so shaped as to be received in the aforesaid extension, thereby to permit a horizontal movement of the screen in the frame and a 10 disengagement of the vertical edges of the screen from the grooves, the grooves and the extension being extended but part way 15 through the stiles.

In testimony that I claim the foregoing as 20 my own, I have hereto affixed my signature.

JAMES WATSON.
